UNITED STATES PATENT OFFICE.

BURT E. TAYLOR, OF MOUNT VERNON, NEW YORK, ASSIGNOR TO BORDEN'S CONDENSED MILK COMPANY, OF NEW YORK, N. Y., A CORPORATION OF NEW JERSEY.

EVAPORATING APPARATUS.

1,308,819.

Specification of Letters Patent.

Patented July 8, 1919.

Application filed May 10, 1918. Serial No. 233,746.

To all whom it may concern:

Be it known that I, BURT E. TAYLOR, a citizen of the United States, and a resident of Mount Vernon, county of Westchester, 5 and State of New York, have invented certain new and useful Improvements in Evaporating Apparatus, of which the following is a specification.

My present invention relates to apparatus 10 used in aid of evaporating, or otherwise treating in order to concentrate them, liquids containing solids in suspension, for example milk, and more particularly to those types of such apparatus disclosed in Letters Patent 15 No. 552455 to Thiesen, or No. 878997 to Payne, and which comprise a cylindrical temperature-transmitting drum, or container, within which there is, by aid of centrifugal force, or otherwise, imparted to the 20 liquid the form of a continuous, continuously moving, thin film, or sheet, bearing against the temperature-transmitting interior surface of the drum. Experience has demonstrated, particularly in the milk and 25 kindred fields, the importance, in analogously employed apparatus, of instrumentalities capable of, during evaporation, at frequently repeated intervals, yieldingly wiping from the thus functioning surface 30 thereto adhering thickening portions of the liquid, as per the process disclosed and claimed in Letters Patent No. 1221024 to Campbell.

The objects of my present invention comprise provision of novel means whereby, 35 during operation, such wiping of the interior temperature-transmitting surfaces of such drums can be more effectively and economically effected, and with less injury to 40 the liquid, as well as to the evaporated, or concentrated, final products, including particularly such of these as are composed of, or contain, substances which, as in milk, are 45 peculiarly susceptible to injury from under heating, percussion, compression, or bacterial infection.

I attain my objects by aid of the devices 50 illustrated in the accompanying drawings, in which—

Figure 1 is a central vertical sectional

view of the drum and some of its accessories, taken on the line A—A of Fig. 2, and including also a perspective view of some elements, including the shaft, the wipers and the train of elements connecting them; 55

Fig. 2 is a sectional view taken on the line B—B of Fig. 1 and viewed in the direction of the arrow;

Fig. 3 is, on enlarged scale, a fragmentary 60 end view showing one of the body, and one of the end wipers, and also the shaft in section, and the said train of connecting elements;

Fig. 4 is a rear view of the parts shown in Fig. 3, except the end wiper, and seen in 65 the direction of the arrow d of Fig. 3;

Fig. 5 is, on enlarged scale, a plan view 70 of one end of the wiper-carrying bar, and showing particularly one of the end wipers;

Fig. 6 is, on similar scale, a partly sectional view of the parts shown in Fig. 5, but taken on the line C—C of Fig. 3, and viewed in the direction of the arrow;

Fig. 7 is, on a still more enlarged scale, 75 a fragmentary, partly perspective and partly sectional, view of a portion of one of the end wipers, and of elements contributing to its support; and

Fig. 8 is a similar view of a part of the wiper-carrying bar, including parts contributing to the support of the end wiper. 80

Similar numerals refer to similar parts throughout the several views.

My apparatus comprises the usual container, or drum 8, having, as is required for 85 production of said film, or sheet, its central axis substantially horizontally disposed (Fig. 1) and a therewith concentric longitudinally coextensive, continuous, solid, or impervious circular interior body surface 8^a 90 (Figs. 1 and 2), and thereto angularly disposed end surfaces 8^b, and the usual accessories, such as supports 9, 9, peripheral jacket 10, having a suitable inlet, 11, for thereinto charging, and outlet 12 for therefrom discharging, temperature-affecting media such as steam, etc.; also an inlet pipe 13 provided with a valve 13^a for regulatedly 95 charging into the drum the liquid to be treated and an outlet pipe 14, provided with 100

a valve 14^a for regulatedly discharging the treated product; also, a suitable outlet 15 for escape, or withdrawal, of vapors of evaporation. In the drum is rotatably mounted, 5 a therewith concentric, rotatory shaft 16, equipped with the usual pulleys 16^a, 16^b, whereby by aid of suitable belting, or other means, the shaft is operatively connected with a source of power not shown, and 10 whereby it is rotated as desired. The said temperature transmitting surfaces of the drum are composed of rapidly temperature transferring material, preferably copper, and the drum is, in this instance, stationary 15 during operation. In one end of the drum, I provide a therewith concentric opening 17 for access to the interior for cleansing and other purposes, and for removal therethrough, for like purposes, of the wiping 20 and film creating instrumentalities carried by the shaft, as hereinafter described. The opening, 17, is closed, during operation, by a circular head plate, 18, detachably secured to the end wall of the drum in any convenient 25 manner, such, for example, as by the screws 18^a. The head plate carries a journal bearing, 18^b, in which rotates one end of the shaft, 16, which is also rotatably carried in another journal bearing, 19, supported 30 by the bracket, 19^a, carried by the opposite end of the drum.

The shaft, 16, serves to rotate within the drum the hereinafter described wiper and film-creating instrumentalities, by aid, in 35 this instance, of a train of connecting elements, as follows: 20 is a hub concentric with the shaft and removably secured thereto by aid of a usual slot and key 21, connection. The hub carries a plurality (in 40 this instance four) of therefrom radially projecting, equally-spaced-apart, spokes, 22, 22^a, 22^b, 22^c. Each spoke comprises, proximate its outer extremity, a tubular bearing, 23, adapted for reception and rotatable carriage 45 therein of a bolt, 24, having, at one end thereof, a head, 24^a, and near the opposite end a perforation, 24^b, for reception of a cotter pin, 24^c, on withdrawal of which the bolt is removable from the bearing. A 50 rigid angle-bar, composed of the unitary, mutually angularly disposed, flanges, 25, 25^a, constitutes another unit of each of the trains of elements connecting each rank of wipers with the shaft, as hereinafter described. This bar extends longitudinally 55 through nearly the entire length of the drum in parallelism with the shaft, 16. The flange, 25^a, carries removably thereto secured, as by a screw bolt, 27^a, (Fig. 3), an 60 oscillatable lever, 27, medially of which is a journal opening through which passes rotatably the bolt, 24. The flange, 25^a, of the bar also carries an arm, 26, secured thereto the same as the lever arm, 27, containing 65 near its extremity a journal opening through

which likewise passes, rotatably therein, the bolt, 24. The bar is thus oscillatably carried by the spoke, 22, which also carries a pair of mutually parallel and oppositely disposed studs, 28, 29, the outer ends of 70 which contain, opposite each other, screw-threaded openings for the reception of the coacting set-screws, 30, 31, alined to bear co-operatively on opposite sides of the upper arm of the lever and whereby the angular 75 disposition thereof relatively to the shaft and to the interior body surfaces of the drum is positively adjustable and maintainable and the tension imparted to the wipers controlled, as hereinafter described. 80

The bar flange, 25, contains a plurality of equally-spaced-apart alike recesses, 25^b, each for reception therein of one of a numerous plurality (disposed in a single rank approximately coextensive longitudinally 85 with the bar) of like spaced-apart, therefrom projecting spring-functioning members or fingers, 32, 32, in this instance and each being a leaf of resilient steel, each removably held in its respective recess by any convenient means, for example a screw, 32^a, (Figs. 3 and 4). Each leaf spring carries, removably secured thereto, as by screws, 32^b, (Fig. 3), and projecting from the free end thereof a tip in this instance, a wiper 90 block, 33, composed of organic material, preferably, as shown in this instance, of hard wood, and preferably so shaped, or disposed, as to permit of its presenting a transversely tapering, or angular, longitudinally extended straight edge, as distinguished from an extended plane, or other, surface, toward the interior body surface of the drum, the taper, or resultant of the angle being preferably directed approximately in the direction of the grain of the 100 wood. The proportions and dispositions of the parts are such that the apices of said edges of the wiper blocks, in a single rank normally contact, in parallelism, with, the 105 interior body surface of the drum, and that substantially interspaces are left open between the blocks, including their operative wiper edges. It should also be noted that the blocks and their said interspaces in any 110 one rank are preferably staggered relatively to those in the next following, or preceding, rank, this being in order that portions of the surface left, by one rank, unwiped, because of the interspaces, may be wiped over 115 by the blocks of the next following rank. Such relatively staggered disposition of the parts seems unnecessary to be specifically shown, as is difficult in the drawings of the present construction. It is readily attained 120 by varying the widths of one or more of the blocks in the one rank as compared with those of others.

It will be understood that, with the above exception, all the wipers addressed to the 130

cylindrical interior body surface of the drum are substantially alike, and that each rank thereof is similarly connected, by exactly, or substantially, similar trains of elements, 5 with the shaft.

It is of importance that, as shown in the drawings, the disposition of the leaf springs, *i. e.* their pitch, or inclination, relatively to the direction of their advance, be such as to 10 result in their drawing their thereby carried blocks behind them while impelling them toward contact with the cylindrical interior surface of the drum, this being in contradistinction to shoving the blocks ahead of 15 the springs whereby the blocks would be made to operate prohibitively for my purposes, as shovels, or scrapers, instead of as wipers.

By aid of the set-screws, 30, 31, the required tension is imparted to the leaf springs, 32, of each rank, and thus the desired degree of pressure of the operative edges of the wiper blocks against the surface of the drum. Also by aid of the set-screws the pressure of the wipers upon the surface is quite accurately regulatable, and thereafter positively maintainable; the individual leaf springs thus provided for each block, and the conformation, and composition, 25 of the wiper edges supplying all required yield and resilience, and this independently and variously to each wiper respectively, according to constantly changing conditions of its own work as compared to 30 that of others of its rank.

The set-screws also enable the operator to positively adjust and maintain the angle of the wiper edges relatively to the thereby affected surface in such fashion as to insure 40 their being yieldingly drawn, or dragged, thereover through the liquid, as distinguished from their being pushed, or shoved, against it and the liquid being thereby as it were, shoveled away; the result being that 45 delicate constituents of the liquid, for example butter fat globules in milk, are exempted from compressions, or impacts, tending to undesirably disrupt them.

For its most successful and sanitary operation, the apparatus depends upon instrumentalities adapted to wipe simultaneously the portions of the interior end surfaces of the drums contacted by the centrifugally actuated cylindrical film of the liquid under 50 treatment, and which are not swept by the side wipers described, this being particularly so in concentrating milk. I accordingly provide a pair of spring-tensioned end-wiper blocks, 34, 34, carried by each of 55 the above described angle bars, in advance of the side wipers. These end wiper-blocks are preferably of the same material as the side-wiper blocks, and are supported and actuated as follows. The flange, 25^a, of each 60 angle bar is cut away adjacent each extrem-

ity thereof, as shown in Fig. 5, thus affording space for installation, there, of the end-wiper and its supports. To the flange, 25^a, there is secured, as per bolts, 35, (Figs. 5 and 8), one flange, 36, of an angle-bar to 70

the other flange, 36^b, of which there are bolted the jaws, 37, within which is slidably disposed a carrier member, or movable inner-jaw, 38, within which is, in turn, slidably supported one of the end-wiper blocks, 75 34, composed, preferably, of material similar to that of the side wiper blocks, and analogously tapered so as to present a longitudinally extended, transversely angular, operative edge to the interior end surface of 80 the drum, as indicated in Figs. 5 and 6, and see also Fig. 7. It will be noted that the end blocks are located in almost contacting proximity to, without actually touching, the cylindrical interior body surface of the 85 drum, and that they wipe the end surfaces very briefly antecedently of the wiping of the sides by the other blocks, 33. (See Fig. 3). Correspondingly, the two terminal units of each rank of side wiper blocks, 33, do almost, but not quite, contact with the interior end surfaces of the drum. Though this construction leaves the extreme corner between the two surfaces literally unwiped, the violent motions imparted to the liquid therewith in contact by the passage in such close proximity thereto of the one wiper followed, at such a brief interval, by another, operating in a different plane, suffice, usually, to wash away any injurious adhesions of the 90 liquid, or its constituents, to the said literally unwiped, and almost negligibly small, surfaces.

The end blocks, 34, are movably and removably supported in their aforesaid disposition, and constantly yieldingly forced to their operative contact with the interior end surfaces of the drum as follows: A reciprocatable spindle, 39, (Figs. 5, 6, and 7), extends slidably through an opening therefor 105 in the rear of the jaws, 37, and of the carrier, 38, being also further supported slidably by extending through a suitable opening in the stud, 40, carried by the flange, 36^a. A pin, 41, is removably carried by the spindle which is threaded through an expansile 110 helical spring, 42, the extremities of which bear respectively against said pin and stud. The spindle is provided with a T head, 43. In the rear of the block, 34, is countersunk a 115 recess, 34^a, adapted to receive the T head and thus prevent lateral movement of the block within the carrier, 38. The T head also bears against the block in the direction of the end surface, 8^b, the length of the block 120 being such as to afford a slight clearance, or space, 44, (Fig. 6) to accommodate recoil. One end of the T head, 43, is guided and 125 slidably supported by passing through a slot, 45, in the jaws, 37. The construction is 130

such that the block is constantly yieldingly spring-impelled toward the end surface, or should the block by reason of swellings, or otherwise, jam in the carrier, then in that case both block and carrier are together so impelled, one object of the carrier being to safeguard against such jamming.

The construction is such that the parts of my apparatus are readily separable, as for 10 cleansing, which is particularly important when milk is being treated. To withdraw and sufficiently separate the aforesaid devices operating within the drum, it is only necessary to remove the head, 18, and turn 15 the set screws, 30, 31, so as to bring the external periphery of the four groups of wipers into a circle sufficiently small to enable them together with the hub, 20, and their respective trains of connecting members to be pulled along and off of the shaft, 16, through the opening, 17. After which, by withdrawing the cotter pins, 24^b, and the bolts, 24, the thereby connected parts are further separable and so on indefinitely as 25 per the construction described. As to the end blocks, 34, and their spring tensions and other accessories, these also are readily separable, after their withdrawal from the drum, as above described, by merely pulling the 30 blocks out of their carriers, 38, withdrawing the pins, 41, withdrawing the spindles, 39, and thereafter the carriers, 38, etc.

Operation and effects.—The liquid to be treated, for example milk to be evaporated 35 or pasteurized, etc., is fed, or allowed to flow, into the drum through the inlet, 13, and, controlled by the valve, 13^a, in such quantity and at such rates as may be indicated. Rapid rotation of the shaft correspondingly 40 moves the blocks, causing them to wipe the interior surface of the drum and to sweep against and through the liquid to the body of which is thus communicated both rotary and horizontally progressive movements, the 45 centrifugal tendency of which assist in spreading and maintaining the liquid in the form of a continuous, continuously moving, attenuated film bearing against the interior temperature-transmitting surface of the drum. This surface being, for example, heated, as may be indicated, evaporation follows correspondingly, and the liquid 50 evaporated to the degree desired, finally passes out of the drum through the outlet, 55 14, to be thereafter marketed, or further treated, as may be desired. The operation may thus be continuously carried on, or intermittently, as desired. The blocks serve to constantly and immediately remove from 60 immediate contact with the operative surfaces of the drum all thereto most proximate thereby unduly heated, thickened, and thereto unduly adhesive, portions of the liquid, thus promoting homogeneity, and expediting 65 uniformity of heat transference through-

out the mass, and also preventing localized overheating and its attendant undesirable results particularly as regards milk products.

Among the important features and results 70 of the invention are the following, viz:

(1.) Connection of the shaft with each of the wiper-blocks respectively by aid of an independent element which is integrally a 75 spring and the free terminal of which carries, as shown, the block, whereby simplicity of construction, cleansibility of parts and regulation and maintenance of required tension are enhanced, and the blocks enabled to act independently of each other to the extent 80 of reaching thereto independently presented deformed portions of the surface of the drum.

(2.) Construction of the blocks, so carried, from organic material, preferably hard 85 wood, and impartation thereto of a longitudinally extended operative wiper edge produced, as regards wooden blocks, by tapering them to such edge in the direction of the grain of the wood, whereby not only is acquisition by the wiper of undesirably high 90 temperatures safe-guarded, but, also, its integral yield and resilience are augmented and undesirable wear and abrasions of the drum and ruptures of constituents of the 95 liquid, such as butter fat globules, etc., of milk, by percussion or compression between the drum and the wiper are minimized.

(3.) Provision of the interspaces between the units of each rank of wipers sufficient to 100 permit free passage therethrough of a substantial portion of the liquid, whereby undue banking up of the liquid in front of the wipers is diminished, and there is insured more rapid and complete return of wiped-up 105 portions to the remainder of the liquid and with minimum impairment of desired uniformity of thickness in the film or sheet thereof.

(4.) Staggered disposition of the units of 110 each rank of wiper-blocks and their interspaces relatively to those of the next following rank, whereby streaks of the heat-transferring surface of the drum left unwiped by the interspaces in one rank, are, in turn, 115 wiped by the blocks of the next rank in the sequence of rotation and desirable transverse circulation of the liquid augmented.

(5.) Provision of means, *i. e.* the oppositely disposed set-screws, coöperating upon 120 opposite sides of an oscillatable member in the train of elements connecting the shaft with the wiper-blocks, whereby the pressure of the latter upon the surface of the drum, and, correspondingly, the aggregate tension 125 of the group of spring-elements in said train is positively regulatable and maintainable.

(6.) The construction and arrangement of the wiper instrumentalities, including their connection with the shaft, and their arrange- 130

ment relatively to the drum, whereby their cleansing and their removal, take down, and re-assemblage, is facilitated.

(7.) The combination with each rank of 5 wiper-blocks of therewith carried spring-tensioned end-wipers, operating in advance thereof, and addressed to the interior end-surfaces of the drum, whereby is insured timely removal of the liquid, or contents 10 thereof, from thereto unduly proximate and heated portions of such end surfaces.

Having now described my invention, what I claim as new and desire to secure by Letters Patent is the following, viz:

15 1. In an evaporating apparatus, a cylindrical container, or drum, having its central axis substantially horizontally disposed and a therewith concentric, longitudinally coextensive, continuous, impervious, circular 20 interior body surface; a rotatory shaft concentric with said axis; supported movably in an orbit concentric with and intermediate said axis and surface a therewith parallel member, or bar, approximately coextensive longitudinally with said surface; carried by said bar a therewith approximately coextensive rank of numerous therefrom toward-said-surface-projecting spaced-apart spring-tensioned fingers each vibrat- 25 able independently of the others and each comprising a thereby detachably carried tip of organic material disposed to normally contact with said surface; and means operatively connecting said bar with said shaft.

30 2. In an evaporating apparatus, a cylindrical container, or drum, having its central axis substantially horizontally disposed and a therewith concentric, longitudinally coextensive, continuous, impervious, circular 35 interior body surface; a rotatory shaft concentric with said axis; supported movably in an orbit concentric with and intermediate said axis and surface a therewith parallel member, or bar, approximately coextensive longitudinally with said surface; carried by said bar a therewith approximately coextensive rank of numerous therefrom toward-said-surface-projecting spaced-apart, spring-tensioned fingers, each vibratable indepen- 40 dently of the others and each comprising a thereby detachably carried tip of organic material disposed to normally contact with said surface; and means operatively connecting said bar with said shaft, said means 45 comprising a spoke carried by said shaft and carried by said spoke an oscillatable lever and a thereon-bearing adjusting set screw.

50 3. In an evaporating apparatus, a cylindrical container, or drum, having its central axis substantially horizontally disposed and a therewith concentric, longitudinally coextensive, continuous, impervious, circular 55 interior body surface; a rotatory shaft concentric with said axis; supported movably

in an orbit concentric with and intermediate said axis and surface a therewith parallel member, or bar, approximately coextensive longitudinally with said surface; carried by said bar a therewith approximately coextensive rank of numerous therefrom toward-said-surface-projecting spaced-apart, spring-tensioned fingers, each consisting of a leaf-spring detachably carrying a tip of organic material disposed to normally contact with 70 said surface; and means operatively connecting said bar with said shaft.

4. In an evaporating apparatus, a cylindrical container, or drum, having its central axis substantially horizontally disposed and a therewith concentric, longitudinally coextensive, continuous, impervious, circular interior body surface; a rotatory shaft concentric with said axis; supported movably in an orbit concentric with and intermediate said axis and surface a therewith parallel member, or bar, approximately coextensive longitudinally with said surface; carried by said bar a therewith approximately coextensive rank of numerous therefrom toward-said-surface-projecting spaced-apart spring-tensioned fingers, each vibratable independently of the others and each comprising a thereby detachably carried tip of organic material disposed to normally 80 contact with, and be yieldingly dragged over, said surface; and means operatively connecting said bar with said shaft.

5. In an evaporating apparatus; a cylindrical container, or drum, having its central axis substantially horizontally disposed and a therewith concentric, longitudinally coextensive, continuous, impervious, circular interior body surface; a rotatory shaft concentric with said axis; supported movably in an orbit concentric with and intermediate said axis and surface, a therewith parallel member, or bar, approximately coextensive longitudinally with said surface; carried by said bar a therewith approximately coextensive rank of numerous therefrom toward-said-surface-projecting spaced-apart spring-tensioned fingers, each vibratable independently of the others and each comprising a thereby detachably carried tip of wood having an angular longitudinally extended straight edge, the apex of which is disposed to contact, in parallelism with, said surface; and means operatively connecting said bar with said shaft.

6. In an evaporating apparatus; a cylindrical container, or drum, having its central axis substantially horizontally disposed and a therewith concentric, longitudinally coextensive, continuous, impervious, circular interior body surface; a rotatory shaft concentric with said axis; supported movably in an orbit concentric with and intermediate said axis and surface a therewith parallel member, or bar, approximately coextensive 125

longitudinally with said surface; carried by said bar a therewith approximately coextensive rank of numerous therefrom toward said-surface-projecting spaced-apart 5 spring-tensioned fingers, each vibratable independently of the others and each comprising a thereby detachably carried tip of wood having a tapered, in the direction of the grain, longitudinally extended straight 10 edge, the apex of which is disposed to contact, in parallelism with, said surface.

7. In an evaporating apparatus, a container, or drum, having a cylindrical interior surface; within said drum a therewith concentric, rotatory, shaft; means to rotate said shaft; a rank of spaced-apart blocks of organic material normally contacting with said surface; means to operatively connect said blocks with said shaft and impel them yieldingly and resiliently toward 15 said contact throughout rotation of the shaft, the said last mentioned means comprising a plurality of interposed springs each carrying one of said blocks; and a pair 20 of coacting, oppositely disposed, set-screws by aid of which the degree of yielding pressure of said blocks against said surface is adjustable and more positively maintainable.

8. In an evaporating apparatus, a container, or drum, having a cylindrical interior surface; within said drum a therewith concentric, rotatory, shaft; means to rotate said shaft; a plurality of spaced-apart ranks of spaced-apart blocks composed of organic material normally in contact with said surface, the blocks and their interspaces of the one rank being staggered relatively to those of another rank; and means to yieldingly and resiliently operatively connect each rank of said blocks with 30 said shaft, the said last mentioned means comprising interposed springs, each carrying one of said blocks.

9. In an evaporating apparatus, a container, or drum, having a cylindrical interior surface; within said drum a therewith concentric, rotatory shaft; means to rotate said shaft; a plurality of spaced-apart ranks of spaced-apart blocks composed of organic material normally in contact with said surface, the blocks and their interspaces of the one rank being staggered relatively to those of another rank; and means to adjustably yieldingly and resiliently operatively connect each rank of said blocks with 40 said shaft.

10. In an evaporating apparatus, a container, or drum, having a cylindrical interior body surface, and a thereto angularly disposed interior end surface; within said drum a therewith concentric rotatory shaft; means to rotate said shaft; a movable block composed of organic material normally contacting with said body surface in almost 50

contacting proximity to the corner between 65 it and said end surface; another such block normally contacting with said end surface and also in almost contacting proximity to said corner; means operatively connecting said shaft with said blocks so spaced apart 70 that, during rotation of the shaft, the block contacting with said end surface shall wipe it briefly antecedently of the wiping of the body surface by the other block.

11. In an evaporating apparatus, a cylindrical container, or drum, having concentric with its central longitudinal axis a throughout uniformly and continuously extending completely circular interior concave surface, and thereto angularly disposed interior end 80 surfaces; within said drum a therewith concentric rotatory shaft; means to rotate said shaft; in sequence not less than three equally-spaced-apart ranks of spaced-apart blocks of organic material normally contacting with said circular surface; and means to operatively connect said blocks with said shaft and impel them yieldingly and resiliently toward said contact throughout 85 their entire rotation by the shaft. 90

12. In an evaporating apparatus, a cylindrical container, or drum, having concentric with its central longitudinal axis an interior concave surface and thereto angularly disposed interior end surfaces; within said 95 drum a therewith concentric rotatory shaft; means to rotate said shaft; a reciprocatable block normally contacting with one of said end surfaces, and means to operatively connect said block with said shaft and constantly, yieldingly impel it toward said end surface during rotation of the shaft.

13. In an evaporating apparatus, a cylindrical container, or drum, having concentric with its central longitudinal axis an interior concave surface and thereto angularly disposed interior end surfaces; within said 105 drum a therewith concentric rotatory shaft; means to rotate said shaft; a reciprocatable block of organic material normally contacting with one of said end surfaces, and means to operatively connect said block with said shaft and constantly, yieldingly impel it toward said end surface during rotation of the shaft. 110

14. In an evaporating apparatus, a cylindrical container, or drum, having concentric with its central longitudinal axis an interior concave surface and thereto angularly disposed interior end surfaces; within said 120 drum a therewith concentric rotatory shaft; means to rotate said shaft; a reciprocatable block normally contacting with one of said end surfaces; means to operatively connect said block with said shaft and constantly, 125 yieldingly impel it toward said end surface during rotation of the shaft; the said last mentioned means comprising a bar opera-

tively connected with the shaft; a jaw carried by said bar; a reciprocatable carrier slidably carried by said jaw and dimensioned to therein normally slidably carry said block; a reciprocatable member disposed to, within said carrier, bear against the block; and a spring disposed and con-

nected so as to constantly, yieldingly force said member against the block and toward said end surfaces.
